UNITED STATES PATENT OFFICE.

DAVID A. CONNELL, OF LOS ANGELES, CALIFORNIA.

COUNTERBALANCING MECHANISM FOR SINGLE-ACTING PUMPS.

1,295,005.

Specification of Letters Patent. Patented Feb. 18, 1919.

Application filed July 31, 1918. Serial No. 247,657.

To all whom it may concern:

Be it known that I, DAVID A. CONNELL, a citizen of the United States, residing at Los Angeles, in the county of Los Angeles and State of California, have invented new and useful Improvements in Counterbalancing Mechanism for Single-Acting Pumps, of which the following is a specification.

My object is to make a counterbalancing mechanism for single acting pumps, and my invention consists of the novel features herein shown, described and claimed.

Figure 1 is a side elevation of a counterbalancing mechanism for single acting pumps embodying the principles of my invention as seen looking in the direction indicated by the arrow 1 in Figs. 2 and 3.

Fig. 2 is a top plan view.

Fig. 3 is a vertical cross section on the line 3—3 of Figs. 1 and 2.

Fig. 4 is a vertical cross section on the line 4—4 of Figs. 1 and 2.

Fig. 5 is a fragmentary vertical sectional detail on the line 5—5 of Fig. 1.

The base 1 is rectangular, flat and of considerable size. The ground at the well where the pump is to be located should be prepared to make a solid foundation 2 for the base 1 so that the base 1 will stand level. The pump casing 3 is inserted downwardly through one end of the base 1 and a flange 4 upon the fitting 5 is screwed upon the upper end of the casing 3 and rests upon the base 1 to rigidly locate the pump relative to the base. The polishing rod 6 extends downwardly through the stuffing box 7 into the pump casing 3 to the plunger. The spout 8 carries the liquid raised by the pump.

The samson post construction 9 comprises angle plates 10 and 11 secured to the base 1 by bolts 12 and 13, posts 14 and 15 mounted vertically upon the base 1 with their lower ends secured to the plates 10 and 11 by bolts 16 and 17, and the brace 18 connecting the upper ends of the posts 14 and 15 together. A fitting 19 is secured to the front face of the upper end of the post 14 and a turn-buckle guy 20 is connected to this fitting 19 and extends downwardly and forwardly and is connected to the clamp 21 mounted upon the pump fitting 5. In a like manner a fitting 22 is connected to the front face of the upper end of the post 15, a turn-buckle guy 23 is attached to this fitting and extends downwardly and forwardly and is

connected to the clamp 21. Fittings 24 and 25 are connected to the rear faces of the upper ends of the posts 14 and 15, turn-buckle guys 26 and 27 are connected to these fittings and extend backwardly, downwardly and outwardly and are connected to fittings 28 and 29 secured to the base 1, so that by manipulating the turn-buckles 30, 31, 32 and 33 the guys may all be tightened to hold the samson post construction 9 rigid relative to the base 1 and rigid relative to the pump fitting 5 so that in the operation of the pump the parts will not yield or get out of line.

Bearings 34 and 35 extend upwardly from the ends of the brace 18, the walking beam bearing 36 is mounted between the bearings 34 and 35 and held in place by a pivot bolt 37, the walking beam 38 is rigidly fixed to the bearing 36, the bearing beam being located at the bottom and longitudinal center of the beam, so that the beam may vibrate back and forth from a horizontal plane. A radius head 39 is formed integral with an attaching plate 40 having a longitudinal slot 41, and the plate 40 is placed upon the forward end of the beam 38 and a bolt 42 is inserted downwardly through the slot 41 and through the beam so that by loosening the bolt the head 39 may adjust to and from the pivot pin 37. Links 43 and 44 are connected to the head 39 by a bolt 45 and extend downwardly on the opposite sides of the head 39 and are connected to a clamp 46 adjustingly mounted upon the polishing rod 6.

A bearing 47 is fixed upon the rear end of the beam 38, a section of pipe 48 is mounted in the bearing 47 and connecting rods 49 and 50 are inserted upwardly through the ends of the pipe 48 and held in place by nuts 51 and 52.

The bearings 53 and 54 are fixed to the front faces of the posts 14 and 15, a bearing 55 fits between the bearings 53 and 54, a lever 56 extends between the posts 14 and 15 and is connected to the bearing 55, a bearing 57 is secured to the lower face and rear end of the lever 56, a pipe 58 is mounted through the bearing 57 and the lower ends of the rods 49 and 50 are inserted downwardly through the ends of the pipe 58, there being nuts 59 and 60 upon the lower ends of the rods 49 and 50. A weight box 61 is mounted upon the rear end of the lever 56 between the rods 49 and 50, and strap loops 62 and 63 are placed around the rods 49 and

50 and secured to the weight box 61, said loops being long enough to allow the rods 49 and 50 to vibrate to a limited extent, and so that when the rods 49 and 50 are removed 5 from the pipe 48 the loops 62 and 63 will hold the rods upright, as shown in dotted lines in Fig. 1. A block 64 is mounted upon the base 1 under the lever 56, and blocks 65 and 66 may be placed on top of the block 64 10 so as to support the lever 56 and the weight box 61 when it is desired to disconnect the rods 49 and 50 from the pipe 49 so that the walking beam may be swung upwardly, as shown in dotted lines in Fig. 1, when it is 15 desired to pull the pump, or the like.

Angle irons 67 and 68 are secured to the beam 38 and a post 69 is mounted with its lower end between the angle irons 67 and 68, the post being in direct line with the pivot 20 bolt 37 and the post being rigidly secured to the angle irons and resting upon the beam. Braces 70 and 71 connect the upper end of the post 69 to the beam 38, a bearing 72 is connected to the upper end of the post 25 69, a clevis 73 is connected to the bearing 72, and the cable 74 has a hook 75 engaging the clevis 73. In practical operation the cable 74 is connected to a pumping jack so that as 30 the jack rotates or operates, the beam 32 is vibrated to work the pump rod up and down.

The windmill rod 76 is connected to a reducing coupling 77, a section 78 of large pipe is screwed into the lower end of the reducing coupling 77, a sleeve 79 is slidingly 35 mounted upon the polishing rod 6 within the lower end of the pipe 78, and a clamp 80 has a bearing 81 clamping the lower end of the pipe 78, and a bearing 82 clamping the polishing rod 6, so that when the clamp 80 is 40 tightened the windmill rod 76 is connected to the pump rod 6 and the operation of the windmill will operate the pump, and when the clamp 80 is loosened the bearing 82 and sleeve 79 will slide upon the polishing rod.

45 The mechanism may be operated either from a windmill, or the like, through the stem 76, or from a jack through the cable 74.

The weight 83 in the box 61 may be of rock, sand, earth, scrap-iron, or any convenient material, and may be increased or decreased at will so as to counterbalance the pumping mechanism to the desired extent.

I call especial attention to the advantage of using the counter lever 56 and the weight 55 box 61, instead of applying the counterbalancing weight direct to the beam 38. Necessarily the samson post construction 9 is of considerable height, which may be six or eight feet, and in order to counterbalance the pump rods, etc., on a deep well pump, the weight 83 may be a ton, and it is a great deal easier to handle this weight in the box 61 near the ground than it would be to handle it upon the walking beams 38. Furthermore, 60 it frequently happens that it is desired to

throw the walking beam 38 out of operative position disconnected from the pump rods and pull the pump rods, or perform other operations, and a simple way to do this is to place the blocks 65 and 66 upon the block 64 70 under the counter lever 56 so as to support the weight 83 in the box 61; then the rods 49 and 50 may be disconnected from the beam 38 either by removing the nuts 51 and 52, or by removing the cap 84 of the bearing 47, 75 then the rods 49 and 50 may be tipped backward, as shown by dotted lines in Fig. 1, and the rods will be supported by the loops 62 and 63 while the walking-beam mechanism is tilted out of use, as shown in dotted lines. 80 Then, furthermore, the weight 83 may be omitted from the box until the job is set up ready to run and this weight may be shoveled into the box from any earth or other material that may be handy, and when the apparatus is torn down the weight is dumped and thrown away. An equal counterbalance weight upon the beam made of cast-iron, or the like, would have to be transported from 85 a foundry and would cost considerable 90 money, and it would require a derrick and considerable work to elevate the weight and place it in position upon the beam and then it would be upon the beam and could not be put out of use or disconnected from the 95 pumping mechanism.

Various changes may be made without departing from the spirit of my invention as claimed.

I claim:

1. A counterbalancing mechanism for deep well pumps comprising a samson post, a main beam pivotally mounted horizontally across the top of the samson post, means of connecting one end of the main beam to a 105 pump rod, a counter beam pivotally connected to the lower part of the samson post and parallel with the opposite end of the main beam from the pump rod, means for removably connecting the free end of the counter 110 beam to the corresponding end of the main beam, means for mounting a weight upon the end of the counter beam and means for connecting power to the main beam.

2. A counterbalancing mechanism for deep well pumps comprising a base, a samson post rigidly connected to the base, a main beam pivotally mounted horizontally at the top of the samson post, means for connecting one end of the main beam to a pump rod, a counter beam pivotally connected to the lower part of the samson post below the opposite end of the main beam from the pump rod end, means for removably connecting the free end of the counter beam to the corresponding end of the main beam, a weight box mounted upon the free end of the counter beam, and means for connecting power to the main beam.

3. A counterbalancing mechanism for deep 130

well pumps comprising a base, a samson post rigidly mounted vertically upon the base, a main beam pivotally connected to the top of the samson post, means for connecting one 5 end of the main beam to a pump rod, a counter beam pivotally connected to the lower end of the samson post and pivotally connected with the opposite end of the main beam from the pump end, means for removing 10 ably connecting the free end of the counter beam to the corresponding end of the main beam, a weight box upon the free end of the counter beam, a block upon the base under the counter beam and removable blocks adapted to be placed upon the top of the 15 first block to support the counter beam and weight when and while the main beam is disconnected.

In testimony whereof I have signed my name to this specification.

D. A. CONNELL.
